CLAIM

The ornamental design for a fishing reel body, as shown and described.

DESCRIPTION

FIG. 1 is a perspective view of the top, front and right side of a fishing reel body showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view similar to FIG. 1 of a second embodiment of the fishing reel body;

FIG. 9 is a front elevational view thereof;

FIG. 10 is a rear elevational view thereof;

FIG. 11 is a top plan view thereof;

FIG. 12 is a bottom plan view thereof;

FIG. 13 is a left side elevational view thereof; and,

FIG. 14 is a right side elevational view thereof.

The broken line showing of environment in the drawings is for illustrative purposes only and forms no part of the claimed design.
